PAPER DISH AND METHOD AND APPARATUS
OF FORMINGRobert E. Rutledge, Kalamazoo, Mich., assignor
to Sutherland Paper Company, Kalamazoo,
Mich.

Application January 20, 1934, Serial No. 707,481

9 Claims. (Cl. 229—2.5)

The main objects of this invention are:

First, to provide an improved paper dish pressed from flat blanks which is very strong and rigid even when formed of light stock.

5 Second, to provide an improved paper dish having these advantages in which the strain upon the stock in forming is minimized.

Third, to provide an improved pressed paper dish which is very attractive in appearance.

10 Fourth, to provide a method of forming paper dishes embodying these advantages in which the stock in the formed dish is so disposed that the displacing strain thereon is minimized and the resultant dish is relatively rigid and attractive in appearance.

15 Fifth, to provide an improved method of forming paper dishes in which the number of defectives produced is greatly reduced when compared to the defectives produced by the methods now in vogue or commercially practiced.

20 Sixth, to provide an improved forming apparatus for dishes which enables a large output with a minimum of defective dishes.

25 Objects relating to details and economies of my invention will appear from the description to follow. The invention is defined and pointed out in the claims.

30 A structure which is a preferred embodiment of my invention is illustrated in the accompanying drawings, in which:

Fig. 1 is a fragmentary view mainly in section on a line corresponding to line 1—1 of Figs. 2 and 3 of my improved machine or apparatus, a single unit being illustrated.

35 Fig. 2 is a fragmentary plan view of the female die.

Fig. 3 is a fragmentary inverted view of the co-acting male die.

40 Fig. 4 is a plan view of the preferred embodiment of my invention.

Fig. 5 is an enlarged side or edge view.

Fig. 6 is an enlarged fragmentary section on line 6—6 of Figs. 4 and 5.

45 Fig. 7 is a plan view of a modified form of my invention, certain features only of the invention being shown in this embodiment.

Fig. 8 is an enlarged fragmentary view on line 8—8 of Fig. 7.

50 My improved dish in its preferred embodiment shown in Figs. 4, 5, and 6, comprises a bottom 1 and side wall 2, the side wall having a down-turned rim 3. The bottom 2 merges into the side wall with a reverse curve providing an annular bead 4 at the base of the side wall.

55 The bottom of this preferred embodiment has a

flat central portion 5 and radial substantially spaced inwardly tapered ribs 6 extending inwardly from this annular bead. These ribs merge or fade into the flat portion of the bottom.

The side wall of the dish has radial flute-like corrugations 7 which extend from the outer edge of the dish over its curved rim and to a point indicated at 8 which is above but adjacent the bottom of the dish. These flute-like ribs or corrugations taper inwardly so that they fade out 10 at this point or zone 8. The resulting dish is very strong and rigid even when formed of relatively light stock and is attractive in appearance. The rim is stiffened so that the dish itself may be picked up by grasping the rim and side wall 15 without the objectionable springing or yielding commonly incident to paper dishes.

A further advantage of these flute-like ribs in the side wall and rim is that the dish may be formed without undue displacement of the stock 20 during the forming operation; that is, such displacement of the stock that will result in folds and tears and cracks which commonly result in a relatively large percentage of defective dishes in the manufacture of pressed dishes in accordance with the methods commonly employed.

The flutings or corrugations of the rim and side wall are highly desirable without the special bottom features but the bottom conformation and the side wall conformation result in a very rigid 30 dish as well as one which is attractive in appearance.

In the embodiment of my invention shown in Figs. 7 and 8, the dish 9 has a polygonal rim 10, the side wall 11 and the rim being provided with 35 corrugations or flutings 7 as in the preferred embodiment. The side wall of this embodiment is stepped at 12, the corrugations or flutings fading out at 13 adjacent the top of the step 12.

Other shapes may be satisfactorily produced 40 embodying certain of the features of my invention.

In Figs. 1, 2, and 3, I illustrate an apparatus or machine for forming my improved dishes, 14 representing the bed of the machine and 15 a reciprocating plunger. I have illustrated but a single unit but it will be understood that in practice a plurality of the die or forming units are provided. The machine consists of a female die 16 and a coacting male die consisting of an inner 45 member 17 and an outer annular coacting member 33. The female die is supported on the die block 19 mounted on the bed of the machine, this being designed to receive a heating unit 20. The knock-out 21 is provided with a disk-like head 22, the 50

face of which is flush with the bottom of the die. A fragmentary plan view of the female die is shown in Fig. 2 and this consists of the bottom portion 23 and the side wall portion 24 terminating in a down-curved rim portion 25. The rim and side wall portions have inwardly tapered corrugations or flutings 26 which merge into the side wall or flat portion thereof at a point adjacent but above the bottom. Only a portion of these flutings are shown but it will be understood that they extend around the entire circumference of the female die member.

10 The bottom is provided with a raised rib 27 which merges into the side wall with a reverse curve 28. This rib 27 is annular and forms the bead 4 of the dish. The female die has inwardly tapered ribs 29 which form the ribs 6 of the dish. The inner male die member 17 is formed to complement the female die member; that is, the parts 15 thereof with which it coacts, the male die member having on its side wall portion inwardly tapered corrugations 30 complementing the inner portions of the corrugations 26 of the female die member. It has an annular groove 31 complementing the annular rib 27 of the female die member and radial grooves 32 complementing the radial ribs 29 of the female die member.

20 The outer annular male die member 33 has a rim forming portion 34 which complements the side wall portion of the male die member and coacts with the outer rim portion of the female die member. This outer die member 33 has corrugations 35 aligned with the corrugations 25 of the male die member when the forming dies are 25 closed.

25 The die member 17 is mounted upon the die block 36 which carries a heating element 37. The die member 33 is reciprocatingly mounted on the die block 36 and plunger 15, guide rods 38 being 30 provided slidably engaging the ears 9 on the die member 33. Coiled springs 40 are arranged on these guide rods and act to urge the die member forwardly, so that as the plunger is advanced, the outer die member 33 will first engage the work 41, 35 as shown in Fig. 1, which has been positioned upon the female die member. The plunger 15 is indicated in a slightly advanced position. As advancement continues, the die member 33 is yieldingly advanced to engage the work although it 40 will draw in somewhat due to the center engaging weight 42 reciprocatingly disposed through the inner male die member and engaging the work, as shown in Fig. 1. As the dies are closed, the work is gradually conformed, the edges being 45 drawn inwardly and the corrugations in the side wall and rim formed and also the bottom conformations produced.

50 The conforming stresses are so distributed that there is no serious rupturing or breaking or folding of the stock, the flutings caring for the excess stock in the rim resulting from the dishing action of the dies. The resulting product is highly attractive in appearance and is very strong and rigid 55 considering the stock employed.

55 The simultaneous forming of the flutings with the dishing of the blank distributes the stock uniformly throughout, and I am enabled to produce highly satisfactory dishes with a minimum of waste or defective dishes.

70 I have illustrated and described my improvements in a highly practical embodiment thereof. I have not attempted to illustrate or describe various adaptations which are possible as it is believed that this disclosure will enable those skilled

in the art to embody or adapt my improvements as may be desired.

Having thus described my invention, what I claim as new and desire to secure by Letters Patent, is:

5 1. A pressed paper dish comprising a bottom and an outwardly flaring side wall terminating in a down-turned curved rim, the bottom merging into the side wall with a reverse curve providing an upstanding annular bead in the bottom adjacent the side wall, the bottom also having a flat central portion and raised ribs tapering inwardly from the said bead and merging into the flat central portion, the side wall and rim having inwardly tapered flute-like radial corrugations extending to the edge of the rim and fading out at a point above but adjacent to the curve joining the side wall and bottom.

2. A pressed paper dish comprising a bottom and an outwardly flaring side wall terminating in a downwardly curved rim, the bottom having an upstanding annular bead adjacent the side wall, the bottom also having a flat central portion and raised ribs tapering inwardly from the said bead and merging into the flat central portion, the side wall and rim having inwardly tapered flute-like radial corrugations extending to the edge of the rim and fading out at a point above but adjacent to the bottom.

3. A pressed paper dish comprising a bottom and an outwardly flaring side wall terminating in a down-turned curved rim, the bottom merging into the side wall with a reverse curve providing an upstanding annular bead in the bottom adjacent the side wall, the side wall and rim 35 having inwardly tapered flute-like radial corrugations extending to the edge of the rim and fading out at a point above but adjacent to the curve joining the side wall and bottom.

4. A pressed paper dish comprising a bottom and an outwardly flaring side wall terminating in a down-turned curved rim, the bottom having an upstanding annular bead adjacent the side wall, the side wall and rim having inwardly tapered flute-like radial corrugations extending to 45 the edge of the rim and fading out at a point above but adjacent to the bottom.

5. A pressed paper dish comprising a bottom and an outwardly flaring side wall terminating in a down-turned curved rim, the side wall having inwardly tapered flute-like radial corrugations extending through and to the outer edge of the rim.

6. A pressed paper dish having an outwardly flaring side wall terminating in a down-turned curved rim, the side wall having radial flutings or corrugations extending through and to the outer edge of the rim and gradually tapering inwardly and merging into an unribbed zone adjacent the bottom of the dish.

7. A pressed paper dish having an outwardly flaring uniformly corrugated side wall terminating in a down-turned curved rim, the radial flutings or corrugations extending through and to the outer edge of the rim and gradually tapering inwardly.

8. A pressed paper dish comprising a bottom and an outwardly flaring side wall, the bottom merging into the side wall with a reverse curve providing an upstanding annular bead in the bottom adjacent the side wall, the bottom also having a flat central portion with raised ribs tapering inwardly from the said bead and merging into the flat central portion.

9. A dish comprising a bottom and an outwardly flaring side wall terminating in a down-turned curved rim, the bottom merging into the side wall with a reverse curve providing an upstanding bead in the bottom adjacent the side wall, the bottom also having a flat central portion and raised ribs tapering inwardly from the said bead

and merging into the flat central portion, the side wall and rim having inwardly tapered flute-like corrugations extending to the edge of the rim and fading out at a point above but adjacent to the curve joining the side wall and bottom. 5

ROBERT E. RUTLEDGE.
